UNITED STATES PATENT OFFICE.

FRANK BATTER, OF PORTLAND, OREGON.

TOILET FIXTURE FOR MOUNTAIN-AIR SANITARIUMS.

Original application filed May 21, 1920, Serial No. 383,180. Divided and this application filed September 5, 1922. Serial No. 586,200.

To all whom it may concern:

Be it known that I, FRANK BATTER, a citizen of the United States, and a resident of Portland, county of Multnomah, and State of Oregon, have invented a new and useful Improvement in Toilet Fixtures for Mountain-Air Sanitariums, of which the following is a specification.

This invention relates to structures in which can be artificially maintained such atmospheric conditions of temperature, pressure, humidity and so forth as may be dictated by the state of a patient. Previous 10 patents of mine, No. 904,172; 1,107,744; and 15 1,107,745, have dealt with atmospheric pressure or rarefied conditions for simulation of high altitudes.

This application is filed to cover the patentable subject matter divided out of the 20 patent granted to me August 28, 1923, No. 1,466,652, for portable mountain air sanitarium, the division being made in compliance with the requirements of the examiner in charge of the last mentioned application.

The specific object of my present invention, however, is to provide a toilet room in which pressure conditions are so controlled as to permit normal use of the toilet fixtures 30 without interference with the artificial atmospheric conditions in the toilet room.

I have shown a preferred design and arrangement of parts in the accompanying drawings, in which:

35 Fig. 1 is an end elevation, partly in section, of the toilet room and related apparatus; and

Fig. 2 is an end elevation at right angles thereto showing valve operating mechanism.

40 The toilet room may be provided with any usual fixtures as the tub 230, the lavatory 231 and closet 232. A drainage tank 233 is provided, the various toilet room fixtures being connected thereto by pipes 234 and 235. A discharge pipe 237 from the drainage tank 233 to a cess pool is provided. In

45 the connections between the toilet fixtures and the tank is a valve 236 and in the aforesaid discharge connections from the tank 50 a valve 238, pipe 239 furnishes a vent for the tank controlled by a valve 240 and pipe 241 controlled by the valve 242 and having a disinfectant receptacle, shown diagrammatically as 243, is connected to the air exhaust system of the sanitarium, of which the

toilet room is a part. It is to be understood that the disinfectant receptacle contains 60 disinfecting material preferably granular which is held against inadvertent dislodgement by the usual screen-like container. It is provided so that offensive odors will not pass into the sanitarium. Pipe 245 controlled by valve 246 is arranged to deliver 65 flushing water from the main to the tank both near the bottom by the angular portion 247 and the vertical portion 248 and by the vertical portion 249 to the interior of the vertical cylinder 250 supported by braces 251 coaxially with the tank.

When the valves 236 and 242 are open 70 and the remaining valves closed, it is evident that there will be a direct air connection through the pipe 241 and thus the atmospheric conditions in the drainage tank will 75 be the same as in the toilet room, which will permit the normal use of the toilet fixtures. When however, it becomes necessary to empty the drainage tank the position of the valves is changed so that the valves 240, 238 and 246 are open and the remaining 80 valves closed. This shuts off the toilet room from the tank and from the air exhaust system and throws it into communication with the atmosphere and sewer connections and admits flushing water.

85 The various valve stems *p*, *q*, *r*, *s*, *t* are parallel and may have their far ends supported in bearings *p'*, *q'*, *r'*, etc. They have adjacent their far ends operating quadrants or sectors which may be located in the same 90 plane for co-action, each with one of a series of suitably located racks carried by an upright reciprocable frame 260 slideable up and down in brackets 261, extending thru the floor of the toilet room into the same and 95 having on its upper end a rack 262 with which meshes the last of a train of gears, 263, 264 and 265 manually movable by the crank 266. The stem of valve 236 is provided with a toothed quadrant 236' with 100 which co-acts rack 236'. The stem of valve 238 is provided with a quadrant 238' operated by a rack 238'. Valve 240 has on its valve stem toothed quadrant 240' actuated by rack 240'. Similarly valve 242 105 carries on the end of its valve stem a toothed quadrant 242' actuated by a rack 242'. To avoid interference the quadrants are alternately oppositely faced and some of the valves are carried on one side of the recipro- 110

cating frame and some on the other facing the quadrants which they are designed to actuate. Each of the quadrants on the various valve stems is provided at each end 5 with a long tooth 252 which enables the rack to pick up the corresponding quadrant and move it into mesh with the rack teeth in whichever direction the frame is moving.

The operation of the valves, assuming 10 them to be in normal condition, that is, with the valves 236 and 242 open, is as follows: The reciprocating frame or cross head 260 carrying the various racks moves down, the rack 236² coacting with quadrant 236' starting to close valve 236. Shortly thereafter rack 242² begins to actuate valve 15 242 thru its quadrant 242'. This closes the connection between the tank and the exhaust. The further movement of the cross head after the closing of these valves brings 20 the rack 240² into mesh with the quadrant 240' to open the vent valve 240. When this valve is open the rack 238² actuating the quadrant 238' opens the valve 238 in the discharge pipe. Shortly after this valve 25 starts to open the rack 246² actuating the quadrant 246' opens the valve 246 in the water pipe admitting water for flushing the tank. It will be obvious that when the 30 cross head is moved in the opposite direction the reverse movement will take place and the valves be restored to their normal position. The racks may conveniently be made adjustable by providing them with 35 bolts 267 passing thru slots 268 and having nuts 269 countersunk so as to be below the face of the frame.

In Figure 1 I diagrammatically illustrate 40 an air exhausting fan 270 within the sanitarium which has an exhaust pipe 271 extending outwardly through the walls and opening into the atmosphere, said exhaust pipe also connects with the vent pipe 243' from the receptacle 243.

45 I have illustrated and described a preferred type of exhausting means in patents granted to myself, Nos. 1,466,652 and 1,466,653, patented August 28, 1923.

I claim:

50 1. In a sanitarium, a toilet room, a toilet fixture or fixtures therein, a receiving tank, connections between said fixture or fixtures, and said tank, a valve in said connections, air exhausting means communicating with 55 said room and tank, a valve between said tank and means, both said valves being normally open to produce the same condition of pressure in the room and tank and permit normal use of the fixtures, a discharge 60 pipe between the receiving tank and the sewer, a vent for the receiving tank, and normally closed valves in said vent and discharge pipe.

65 2. In a sanitarium, a toilet room, a toilet fixture or fixtures therein, a receiving tank,

connections between said fixture or fixtures and said tank, a valve in said connections, air exhausting means communicating with said room and tank, a valve between said tank and means, both said valves being normally open to produce the same conditions of pressure in the room and tank and permit normal use of the fixtures, a discharge pipe between the receiving tank and the sewer, a vent for the receiving tank, normally closed valves in said vent and discharge pipe, and means for operating said valves in a predetermined order. 70 75

3. In a sanitarium, a toilet room, a toilet fixture or fixtures therein, a receiving tank, connections between said fixture or fixtures and tank, means for exhausting air from said room and tank, a valve in the connections between the toilet fixtures and tank, a valve in the exhaust from said tank, a 80 discharge pipe from the receiving tank, a valve therein, a vent in the receiving tank, a valve in the vent, a water pipe for flushing the receiving tank, a valve therein, and means operable as a unit for controlling the 85 position of said valves and opening and closing them in the predetermined order. 90

4. In a sanitarium, a toilet room, a toilet fixture, or fixtures therein, a receiving tank, drainage connections between said fixtures or fixtures and tank, a valve in said connections, an air pump and air exhaust pipes connecting said toilet room, and receiving tank with said pump, a valve in the connection between the receiving tank and 95 pump, a discharge pipe for said tank, a valve in said pipe, a vent pipe for the receiving tank, a valve in the vent pipe, and means for changing the position of the 100 valves from their normal position in which the first two valves named are open and the rest closed to the receiving tank emptying 105 position in which the first two named valves are closed and the rest open and for reversing the operation to return the valves 110 to the normal or position of use.

5. In a sanitarium, a toilet room, a toilet fixture or fixtures therein, a receiving tank, drainage connections between said fixture, or fixtures and tank, a valve in said connections, an air pump and air exhaust pipes connecting said toilet room and receiving tank with said pump, a valve in the connection between the receiving tank and pump, a discharge pipe for said tank, a 115 valve in said pipe, a vent pipe for the receiving tank, a valve in the vent pipe, a water pipe for flushing said receiving tank, a normally closed valve therein, and means for changing the position of the valves 120 from their normal position in which the first two valves named are open and the rest closed to the receiving tank emptying 125 position in which the first two named valves are closed and the rest open and 130

for reversing the operation to return the valves to the normal or position of use.

6. In a sanitarium, a toilet room, a receiving tank, normally communicating with said toilet room, said tank having a second communicating passageway normally cut off from the atmosphere, adjustable means controlling valves in each of said

communicating passageways which are successively reversed by one adjustment of said means, so as to shift the pressure in the receiving tank to atmospheric pressure and emptying said tank, while maintaining the pressure conditions in the toilet room undisturbed. ¹⁰

FRANK BATTER.
